UNITED STATES PATENT OFFICE.

CHARLES A. SULZMAN, OF WATERFORD, NEW YORK.

STOP-VALVE.

SPECIFICATION forming part of Letters Patent No. 431,082, dated July 1, 1890.

Application filed October 18, 1889. Serial No. 327,418. (No model.)

To all whom it may concern:

Be it known that I, CHARLES A. SULZMAN, a citizen of the United States, residing at Waterford, in the county of Saratoga and State 5 of New York, have invented new and useful Improvements in Stop-Valves, of which the following is a specification.

This invention relates to stop-valves of that class in which a pair of vertically-movable 10 gates are arranged to operate by means of a vertical screw-threaded stem or rod, and in which means are employed for forcing the said gates apart laterally and into contact with their seats.

15 My invention consists in certain improvements in the construction of said valves, whereby a combined vertically-sliding and laterally-parting movement of the gates is avoided, by which the construction is simplified, 20 and by which the operation is rendered certain and effective, as will be hereinafter fully described, and particularly pointed out in the claims.

In the drawings hereto annexed, Figure 1 25 is a vertical sectional view of a valve embodying my improvements, showing the valve open. Fig. 2 is a perspective view showing the gates and the operating mechanism separated for the purpose of illustrating the invention more 30 clearly. Fig. 3 is a vertical sectional view showing the valve closed.

Like numerals of reference indicate like parts in all the figures.

1 designates the valve-casing, which in this 35 instance is shown as being T-shaped, one of the arms being provided with a plug 2, which may be adjusted either in one of the vertical arms 3 or in the elbow 4 of the valve-casing, which may therefore at will be used for a 40 straight-way or for an elbow valve. The valve-casing is constructed with the upwardly-extending chamber 5, having a cap 6, through which extends the valve-stem 7, which is journaled in said cap, and provided with a flange 8 to prevent it from being displaced vertically in the latter, an exteriorly-screw-threaded disk 9 being arranged within a flange 10, extending upwardly from the cap 6, to prevent the flange 8 from moving upwardly. The 45 flange 10 is provided at its upper end with a cap or cover 11, having an opening for the 50 passage of the upper end of the valve-stem 7,

which is provided with a hand-wheel 12. The cap 6 and cover 11 may be provided with packing 13 for the purpose of making tight joints. 55

The inner ends of the laterally-extending arms 3 of the valve-casing are ground to form seats 14 for the circular gates 15 and 16, which are adapted to move upwardly into the chamber 5, which extends upwardly from the 60 valve-casing. The inner end of the elbow 4 of the valve-casing is provided with shoulders or recesses 17 to support the gates when the latter are in a lowered or closed position.

18 designates a yoke having an upwardly-extending socket 19. The said yoke and socket are provided with a vertical interiorly-screw-threaded perforation 20, through which extends the lower screw-threaded end of the valve-stem 7. It is obvious that by rotating 70 the said stem the yoke 18 will be caused to travel upwardly or downwardly in the casing, according to the direction of rotation.

The circular gate 15 is provided on its inner side with a segmental recess 21, which 75 forms a bearing, in which is pivotally mounted the inner end of a tongue 22, which extends transversely through the yoke 18. The outer end of the tongue 22 is beveled or wedge-shaped, as will be seen at 23, and rests in a 80 correspondingly-beveled recess 24 in the inner side of the gate 16. The tongue 22 is provided on its upper and lower sides with transverse ridges or ribs 25, adapted to engage the upper and lower ends of the yoke. The tongue 85 22 is also provided with a vertical opening or perforation 26 for the passage of the lower screw-threaded end of the valve-stem 7, said opening 26 being of sufficient diameter to prevent its walls from coming in contact with the 90 valve-stem.

The operation of my invention will be readily understood from the foregoing description, taken in connection with the drawings hereto annexed. When by rotating the valve-stem 95 90 the yoke 18 is caused to travel in an upward direction, it carries with it the tongue 22, which in turn engages the gates, which are thus moved upwardly into the chamber 5 of the valve-casing, thus opening the valve. 100 When the valve-stem is rotated in the opposite direction, the gates 15 and 16 will drop down until they rest upon the shoulders 17, when continuing the operation of the valve-

stem the yoke 18, carrying the tongue 22, is forced in a downward direction, thus causing the beveled end of said tongue to bear against the correspondingly-beveled recess in the gate 16, thereby forcing the gates 15 and 16 apart and into contact with their respective seats. It will be observed that the gates 15 16 are not forced apart or into contact with their seats until they rest upon the shoulders 17 and the downward movement of said gates has completely ceased. Friction and wear upon the faces of the gates are thereby avoided, and leaking of the valve resulting from such wear is prevented. It is also unnecessary to make provision in the valve-casing for any further downward movement of the gates in order to compensate for wear, as has been customary in this class of valves as heretofore constructed.

Having thus described my invention, what I claim, and desire to secure by Letters Patent, is—

1. The combination, with the valve-casing having laterally-extending arms, the inner ends of which are provided with seats, of the circular gates provided, respectively, with a segmental and a beveled recess in their inner faces, a tongue mounted pivotally in the said segmental recess and having a beveled end engaging the beveled recess of the opposite gate, and a vertically-movable yoke inclosing and carrying the said tongue, substantially as set forth.
2. The combination of the valve-casing having the oppositely-extending lateral arms provided with seats at their inner ends, the ro-

tary valve-stem screw-threaded at its lower end, the yoke having an interiorly-threaded perforation adapted to travel vertically upon said valve-stem, the tongue mounted in said yoke and having a beveled end, and the gates mounted upon said tongue, one of said gates being provided with a beveled recess to engage the beveled end of the tongue, substantially as set forth.

3. In a stop-valve, the combination, with the vertically-movable yoke, of the tongue mounted in said yoke and provided with ridges on its upper and lower sides to engage the said yoke and a beveled or wedge-shaped end, and the gates mounted upon said tongue, one of said gates being provided with a beveled recess to engage the beveled end of said tongue, substantially as set forth.

4. The combination of the valve-casing having the seats 14 and the shoulders 17, the rotary valve-stem having screw-threaded lower end, the yoke arranged to travel vertically upon said valve-stem and having the vertically-perforated tongue provided with a beveled end, and the gates mounted upon said tongue, one of said gates being provided with a beveled recess to engage the beveled end of the latter, substantially as set forth.

In testimony that I claim the foregoing as my own I have hereto affixed my signature in presence of two witnesses.

CHARLES A. SULZMAN.
